(57) **CLAIM**

The ornamental design for a toy car, as shown and described.

DESCRIPTION

FIG. 1 is a top plan view of a toy car showing my new design;

FIG. 2 is a bottom plan view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a top, left, rear perspective view thereof;

FIG. 8 is a top, right, rear perspective view thereof;

FIG. 9 is a top, left, front perspective view thereof;

FIG. 10 is a top, right, front perspective view thereof;

FIG. 11 is a bottom, left, front perspective view thereof;

FIG. 12 is a bottom, left, rear perspective view thereof; and, FIG. 13 is an enlarged view thereof taken from the section shown in FIG. 3.

The dash-dot broken lines in FIGS. 3 and 13 are included to show enlarged partial views. All other broken lines represent portions of the toy car that form no part of the claimed design. None of the broken lines form a part of the claimed design. The interior face of the gears adjacent the broken lines forms no part of the claimed design.

1 Claim, 13 Drawing Sheets
